Application May 12, 1955, Serial No. 507,941

Claims priority, application France May 15, 1954

2 Claims. (Cl. 343—857)

This invention relates to a circularly polarized micro-wave antenna having an axial radiation pattern.

It is known to construct circularly polarized micro-wave antennae by arranging, in the same plane, N antenna elements having approximately a quarter-wavelength and making between themselves angles which are equal to

$$\frac{360}{N}$$

degrees and feeding each of these elements with waves having respective phase-differences which are also equal to

$$\frac{360}{N}$$

degrees. French Patent No. 1,032,147, of February 7, 1951, for a "Circularly Polarized Antenna," and British Patent No. 567,201, of the March 5, 1943, provide antennae of this type, which comprise two crossed dipoles excited in quadrature, and United States Patent No. 2,480,182 of August 30, 1949, for an "Antenna," describes an antenna of the same type comprising three quarter-wavelength elements spaced apart by 120° and driven by waves having respective phase-shifts of 120°.

In an ideal circularly polarized antenna, the end of the radiated electric-field vector at a point located on the axis of the antenna describes a polarization circle. At a point the direction of which makes an angle i with the axis of the antenna, the end of the electric vector describes an ellipse of polarization having a ratio, between the axes, of

$$r = \frac{\text{minor axis}}{\text{major axis}} = \cos i$$

In certain applications, it is necessary that the field remains circularly polarized even along directions oblique with respect to the antenna pattern axis. However, polarization does not remain circular out of the axis for large values of the obliquity i when the antenna is formed by a discreet number of quarter-wavelength elements distributed equiangularly.

The object of the present invention is to construct a circularly polarized antenna for microwaves, the radiating element of which is an element which has a revolution symmetry about the axis of the antenna and which gives a circularly polarized field in a wide beam angle.

According to the invention, the radiator of the antenna is a flat circular disc which is excited at N points, that are distributed at equal distances over a circle drawn on one of the faces of the disc, by waves having respective phase-differences which are equal to the angular distances apart between the points of excitation on the said circle.

Other objects and features of the invention will appear on reading the detailed description of an example of embodiment which will now be given with reference to the accompanying drawing in which Fig. 1 is an axial section of the antenna and Fig. 2 shows curves giving the ratio r

2

in terms of the angle i between a given direction and the pattern axis.

The antenna is in the general form of a metallic cylinder 1 which is terminated at the radiating end by a dome 2 of dielectric material. It is fed through a coaxial line 3, to which a wave having a wavelength λ is applied. The internal conductor 4 of this line terminates in a cavity 5 in the form of a probe which couples the line with the cavity.

Leading into the cavity 5 are N coaxial lines which are distributed equiangularly. In the example described, it is assumed that $N=4$, and two lines only, 6 and 8, are seen in the figure. The internal conductors of these lines, namely 7 and 9 respectively, pass into the cavity 5 where they constitute coupling probes.

The diameter of the cavity 5, that of the coupling probes 4, 7, 9 . . . and the characteristic impedances of the input line 3 and of the output lines 6, 8 . . . are conveniently fixed in order that the energy arriving through the input line should be entirely transmitted to the output lines.

The coaxial lines 6, 8 . . . are filled with a dielectric substance having a constant ϵ , on a length l_p , for the line of order p given by:

$$l_p = l_1 + \frac{p-1}{N} \frac{\lambda}{\sqrt{\epsilon-1}}$$

In the example chosen, one may make:

$$l_1 = 0$$

$$l_2 = \frac{\lambda}{4(\sqrt{\epsilon-1})}$$

$$l_3 = \frac{2\lambda}{4(\sqrt{\epsilon-1})}$$

$$l_4 = \frac{3\lambda}{4(\sqrt{\epsilon-1})}$$

In the figure it has been assumed that the coaxial line 8 is entirely filled with dielectric material and that, in the coaxial line 6, the dielectric material is arranged in the form of pieces 14, all but one of which has a length which is a multiple of a quarter of the wavelength in order to eliminate reflection.

In front of the antenna, the external conductors are short-circuited between each other by a plate in which are bored four holes and the internal conductors 7', 9', 10' . . . extend into a chamber 11 and are connected to the disc 12 by screws 13 for example.

The length and the diameter of the conductors 7', 9', 10' . . . , which serve as impedance-matching transformers, are determined by experiment for the purpose of transmitting all the energy arriving through the coaxial lines 6, 8 . . . to the disc 12. The circle, along which the points of connection between the conductors 7', 9', 10' . . . are distributed, and the disc 12 are such that the perimeter of a diametrical section of the disc, reduced by the diameter of this circle, is approximately equal to half a wavelength.

A metallic ring 15, which is screwed to the cylinder 1, eliminates rearward radiation.

Referring now to Fig. 2, the ratio r between the minor axis and the major axis of the polarization ellipse is given in terms of the angle i in two planes passing through the antenna axis. Many curves have been set forth by applicants and curves 16 and 17 are respectively the best and the worst of said curves i. e. the curves for which the ellipticity of the polarization ellipse for a given obliquity is the nearest of and the farthest from unity. It may be seen from line 18 that, if a ratio r better than 80% is required from the antenna, this value is ob-

tained in an angle of approximately 40° on each side of the pattern axis.

What we claim is:

1. A circularly polarized microwave antenna comprising a flat circular disc having a front radiation face and a rear feed face, a single general coaxial feed line, a plurality of particular coaxial feed lines coupled with said single line having outer and inner conductors, all the outer conductors being connected between each other before the disc and the inner conductors being connected to the rear face of the disc at points located over a feed-circle drawn on said face and distributed at equal distances on said circle, and dielectric material plugs inserted in

10

said particular coaxial feed lines to produce phase differences which are equal to the angular distances apart between the points of connection on the said circle.

2. A circularly polarized microwave antenna according to claim 1, in which the perimeter of a diametrical section of the disc, reduced by the diameter of the feed-circle is equal to half the wavelength of the wave radiated by the antenna.
